UNITED STATES PATENT OFFICE.

HAROLD E. NOCK, OF NEWBURYPORT, MASSACHUSETTS, ASSIGNOR TO TOWLE MANUFACTURING COMPANY, OF NEWBURYPORT, MASSACHUSETTS, A CORPORATION OF MASSACHUSETTS.

DESIGN FOR A COMPTOIER OR ANALOGOUS ARTICLE.

Application filed April 1, 1929. Serial No. 30,696. Term of patent 7 years.

To all whom it may concern:

Be it known that I, HAROLD E. NOCK, a citizen of the United States, residing at Newburyport, in the county of Essex and Commonwealth of Massachusetts, have invented a new, original, and ornamental Design for a Comptotier or Analogous Article, of which the following is a specification, reference being had to the accompanying drawing, forming a part thereof.

In the drawing, Figure 1 is a plan view and Fig. 2 is a view in elevation of a comptotier showing my new design.

The dominant feature of my design consists in concentric undulations increasing in width from the base to the upper edge of the bowl, and harmonious concentric undulations on the stem and base of the comptotier or analogous article.

I claim:

The ornamental design for a comptotier or analogous article, substantially as shown and described.

HAROLD E. NOCK.
